UNITED STATES PATENT OFFICE.

WILLIAM H. MELCHER, OF PHILADELPHIA, PENNSYLVANIA.

BRICK-KILN.

SPECIFICATION forming part of Letters Patent No. 293,489, dated February 12, 1884.

Application filed August 24, 1883. (No model.)

To all whom it may concern:

Be it known that I, WILLIAM H. MELCHER, a citizen of the United States, and a resident of Philadelphia, Pennsylvania, have invented 5 certain Improvements in Brick-Kilns, of which the following is a specification.

My invention consists, mainly, of the combination, in a brick-kiln, of a chamber in which the bricks are burned, a combustion-chamber 10 beneath the said brick-burning chamber, a perforated floor of arched brick-work, and sundry fire-places, all substantially as described hereinafter, the object of my invention being to burn all the bricks in the kiln to a 15 uniform condition.

In the accompanying drawings, Figure 1, Sheet 1, is a front view of the kiln; Fig. 2, a vertical section on the line 1 2, Fig. 1; Fig. 3, Sheet 2, a vertical section on the line 3 4, Fig. 2; and Fig. 4, a sectional plan on the line 5 6.

The kiln A is preferably of the quadrangular form shown in Fig. 4, *a a'* being the opposite side walls, and *b b'* the opposite end walls. 25 The structure is separated by a series of brick-work arches into two main compartments or chambers—namely, the upper or burning chamber, D, and beneath the latter the lower compartment or combustion-chamber, E. There 30 are in the present instance two sets, B B', of brick arches, those of one set having their abutments on one side wall, *a*, and the central wall, *d*, and the arches of the other set, B', having their abutments on the opposite side 35 wall, *a'*, and the said central wall. The arches of each set are arranged a short distance—about an inch and a half—apart from each other, the spaces between these arches affording direct communications between the burning-chamber and combustion-chamber beneath. The system of arches with intervening 40 spaces affords, in reality, a perforated floor for supporting the bricks to be burned, and while this floor may consist of continuous 45 arches with openings at frequent intervals, or may be made of perforated bricks, I prefer a succession of arches with intervening spaces in the manner described. The central supporting-wall, *d*, is arched, as shown in Fig. 2, 50 for it is desirable that the combustion-chamber E should extend both laterally and longi-

tudinally to the walls of the structure, and should be as free as possible from all obstructions, the object being to obtain an extended chamber, within which the products of combustion may expand and be disseminated prior to passing through the openings in the floor. 55

When the structure is of quadrangular form, as shown, I prefer to combine with it four fire-places, G, two at each end, as shown in Fig. 4, 60 each fire-place having a grate, *f*, a fuel-door, *h*, and ash-pit door, *i*, as shown in Fig. 2.

When a rapid burning of the bricks is desired, I introduce into the ash-pit air under pressure obtained from any available source; 65 but I prefer for obtaining the desired blast any of the well-known ejectors. Thus in Fig. 1 a nozzle communicating with a steam-pipe, W, is contained within each blast-pipe H, the jet of steam inducing air to rush into 70 the end of the pipe and through the same into the ash-pit.

In the operation of brick-kilns as usually constructed, more or less difficulty is experienced in burning the mass of bricks to a uniform condition—a difficulty which is attributable to the contracted passages or flues formed in stacking the bricks, many of the bricks being thus exposed to the direct action of the products of combustion, and being thus overburned, while others are insufficiently burned. 75 This difficulty is obviated by my improved kiln, in the burning-chamber of which the bricks are so stacked upon the arched and perforated floor that there shall be suitable 80 interstices for the permeation of the products of combustion through the mass. The products of combustion from the fire-places, instead of passing directly to the stacked bricks, as in ordinary kilns, are first disseminated 85 throughout the combustion-chamber E, whence they are distributed alike to all the perforations of the floor, and pass through the same to the stacked bricks. As the kiln is always open at the top, there can be no tendency of 90 the products of combustion to deviate from a direct course, and as these products are disseminated throughout a chamber as extensive, or nearly so, as that which contains the stacked bricks, the result will be the uniform 95 burning of the same. A filling, *t*, Fig. 3, of bricks or fragments of bricks, is placed in 100

the depressions formed at the top of the arches, so as to form a comparatively level floor, the filling being such as to afford a free passage for the products of combustion; or the 5 bricks of the arches may be such that the floor will be level without any filling.

When the kiln is of the quadrangular form shown, I erect braces N, against the opposite side walls, as seen in Fig. 1, so as to enable the 10 said walls to better resist the tendency which the arches, owing to the weight of the stacked bricks, have to thrust the walls outward; but if the kiln be round, the walls may be stayed by bands. The number of sets of arches will 15 depend upon the dimensions of the kiln, and the same may be said as regards the number of fire-places; but it is advisable in all cases that the products of combustion should be introduced into the chamber E at different 20 points, so that the said products may be uniformly distributed throughout the said chamber.

I do not desire to claim, broadly, in a brick-kiln a perforated arched floor irrespective of 25 the character of the floor.

I claim as my invention—

1. A brick-kiln in which the following elements are combined, namely: first, a chamber for containing the bricks to be burned; second, a combustion-chamber underlying the said 30 brick-burning chamber; third, a continuous uninterrupted arched floor perforated throughout between the two chambers for supporting the stacked bricks to be burned; and, fourth, fire-places communicating with the said combustion-chamber, all substantially as set forth. 35

2. The combination of the chambers D and E of the kiln, perforated floor, and fire-places with blast-pipes, through which air under pressure is introduced into the ash-pits of the 40 fire-places, substantially as specified.

In testimony whereof I have signed my name to this specification in the presence of two subscribing witnesses.

WM. H. MELCHER.
